UNITED STATES PATENT OFFICE.

MOSES B. DISKIN, OF NEW YORK, N. Y.

TAPE-APPLYING MACHINE.

1,380,540.

Specification of Letters Patent. Patented June 7, 1921.

Application filed May 8, 1919. Serial No. 295,762.

To all whom it may concern:

Be it known that I, MOSES B. DISKIN, a citizen of the United States, residing at New York, in the county of New York and State of New York, have invented certain new and useful Improvements in Tape-Applying Machines; and I do hereby declare the following to be a full, clear, and exact description of the invention, such as will enable others skilled in the art to which it appertains to make and use the same.

The present invention relates to a machine for applying tape to boxes and other objects.

The object of the invention is the provision of such a machine embodying a novel mechanism for feeding the boxes or other objects and tape, and means for cutting the tape and pressing it down on the boxes or objects.

A further object is the provision of such a mechanism which is so constructed and operable that it can be adjusted for boxes or objects of different sizes, and to apply pieces of tape of different lengths.

The invention also includes novel features of construction to enhance the utility and efficiency of the machine, and to render the construction and operation comparatively simple.

With the foregoing and other objects in view, which will be apparent as the description proceeds, the invention resides in the construction and arrangement of parts hereinafter described and claimed, it being understood that changes can be made within the scope of what is claimed without departing from the spirit of the invention.

The invention is illustrated in the accompanying drawings, wherein—

Figure 1 is a plan view of the machine, portions being broken away.

Fig. 2 is a longitudinal vertical section.

Fig. 3 is a cross section taken on the line 3—3 of Fig. 2.

Fig. 4 is a sectional detail showing the tape feeder moved forwardly.

Fig. 5 is a detail view of the tape pressing means.

The machine embodies a table 1 mounted on a suitable frame 1', and a magazine 2 for the folded cardboard or paper boxes, or other objects, is provided on the table near the rear end thereof. This magazine includes a transverse front wall 3 on the table, the upright side members 4 adjustable

transversely on the table, and the upright rear members 5 adjustable longitudinally on the table, said members 4 and 5 being adapted to be adjusted for boxes, blanks, or objects of different sizes. Although the machine is particularly intended for pasting tape over the meeting edges of folded box blanks to attach the walls of the box together at one corner, it is apparent that the machine can be used for various other purposes when it is desired to apply a tape to an object for one purpose or another. The folded boxes or blanks 6 are placed in a stack in the magazine 2 on the table and are fed forwardly under the wall 3 longitudinally over the table for the taping operation.

In order to feed the boxes 6 forwardly from under the stack in the magazine, a feeder slide 7 is mounted for longitudinal movement in a slot 8 in the table 1 under the magazine, and this slide 7 has longitudinal slots 9 in which are mounted for longitudinal adjustment the blocks 10 having fingers 11 to engage the rear edge of the lowermost box and shove it forwardly when the slide 7 is moved in that direction. The blocks 10 can be adjusted to different longitudinal positions along the slide 7, such as by means of an adjusting screw 11' or the like. This enables the fingers 11 to be adjusted for boxes or objects of different sizes, and also enables the feeder to be regulated so as to move the box or object forwardly the desired distance with respect to the tape applying mechanism. Thus, if the fingers 11 are adjacent to the boxes when the slide 7 is in its rearmost position, then the box will be fed forwardly the maximum distance, whereas if the fingers 11 are shifted rearwardly of the slide 7 so that the slide 7 will move forwardly a certain distance before the fingers 11 contact with the lowermost box in the magazine, then the box will not be fed forwardly the same distance. In this way, the feeder is not only adjustable to feed blanks of different sizes, but is also adjustable to regulate the amount that the box or blank is moved forwardly.

The driving mechanism includes a transverse drive shaft 12 which, through the medium of an eccentric or the like, reciprocates a link or connecting rod 13 pivoted to a lever 14 which is connected by a link 15 with the slide 7, thus reciprocating the slide forwardly and rearwardly in the slot 8.

The feeder above described is for the purpose of moving the blanks or objects from under the stack in the magazine to a position for the application of the tape, and a second feeder is employed for feeding the blanks or objects after the forward end of the tape is put down on the blank. Thus, a feeder wheel 16 is mounted on a transverse shaft 17 below the table 1 and its upper portion extends through an opening in the table so that the blanks pass over and rest on said wheel, in order that when the blanks are pressed down on the wheel and the wheel rotated, said wheel will feed the blanks. The wheel 16 is rotated a predetermined amount, and it has an intermittent forward rotation, the amount of rotation of which can be regulated for blanks of different sizes. A pinion 18 secured on the shaft 17 meshes with a gear wheel 19 mounted on a shaft 20, and an oscillatory arm 21 is carried by the shaft 20 and has pivoted thereto a gripping member 22 sliding on an angular flange 23 provided on one side of the gear wheel 19, said member 22 sliding loosely on said flange, when the arm 21 swings rearwardly, and gripping said flange and turning the wheel with the arm when the arm moves forwardly. The arm 21 is connected by a link 24 with a wrist pin 25 carried by a block 26 adjusted for radial movement in a disk 28 mounted on the driving shaft 12, said block 26 being adjusted by means of a screw 27 or the like to regulate the throw of the arm 21. This enables the amount of movement of the arm 21 to be regulated from a minimum to a maximum amount, in order to regulate the amount of peripheral movement of the feeder wheel 16 according to the distance it is desired to move the blank or object during the application of the tape thereto. Coming to the tape applying and cutting devices, there is a frame 29 overhanging the table 1 and supported at one side thereof for the passage of the blanks under said frame. A slide 30 is mounted for vertical movement in a guide in the frame 29 above the wheel 15, and carries a tape applying roller 31, the position of which with respect to the blank 30 is adjusted by means of a screw 32 or other well known means. This roller 31 when moved downwardly will press the tape down on the blank, and also press the blank down on the wheel 15 so that the blank will be fed by said wheel and the tape pasted on the blank during its movement. Immediately in rear of the roller 31, the frame 29 has a vertical guide 33 with a shear bar 34 at its lower end, and a slide 35 is movable vertically in the guide 33 and has a cutter 36 at its lower end to shear past the shear bar 34, to sever the tape where it passes over the shear bar 34.

65 The tape 37 passes over a roller 38 for

moistening the lower surface of the tape or applying paste thereto, said roller 38 dipping in a tank 39 supplies the moisture or paste. From the roller 38, the paste passes over guide rollers 40 and 41, and thence downwardly under a roller 42 supported by a pair of guide rods 43 projecting rearwardly from the guide 33. A slide 44 is movable on the rods 43, and is connected by a link 45 with a rearwardly extending lug 46 on the slide 35, whereby the vertical movement of the slide 35 will move the slide 44 horizontally or longitudinally on the rods 43. The link 45 has a turn buckle 47 for adjusting it to regulate the movement of the slide 44. It will be noted that when the slide 35 moves upwardly, the link 45 in being pulled with the slide 35, will pull the slide 44 forwardly, and when the slide 35 moves downwardly, the link 45 will shove the slide 44 rearwardly. This slide 44 has a hanger 48 with rollers 49 between which the tape extends forwardly from the roller 42, and said rollers 49 holding the tape therebetween, and pulling it forwardly with the slide 44. The hanger 48 also has a forwardly extending finger 50 projecting over the shear bar 34 to support the forward terminal of the tape. Thus, when the slide 35 is raised, and the slide 44 moved forwardly, the tape will be pulled with the rollers 49 and moved across the shear bar 34 to a point under the clamping roller 31 to be pressed down thereby onto the blank.

A series of pressing rollers 51 are disposed in a longitudinal line in front of the roller 31, and are forced down tightly onto the tape and blanks by means of the screws 52 or the like, in order to press the tape tightly down on the blanks to adhere thereto.

In order to press the tape into the crevice or slit between the adjacent edges of the blank, a longitudinal wire or rod 53 is disposed under the rollers 51 which are provided with annular grooves partially receiving the wire, which extends downwardly slightly from the peripheries of the rollers over the meeting edges of the blanks so as to press the tape down between its edges into the space or crevice between the edges of the blanks. The rear end of the wire 53 has an upwardly projecting shank 54 slideable in a lug 55 provided on the frame 29, and a spring 56 presses the shank 54 down to hold the wire snugly on the tape, and permit it to yield upwardly. The downward movement of the wire 53 at its rear end is limited by an adjustable collar 57 on the shank 54 to seat downwardly on the lug 55.

The operating means for the slides 30 and 35 includes a pair of levers. One lever 58 is fulcrumed at 59 to the frame 29 and one arm is connected, as at 60, to the slide 35, while the opposite arm is connected by a

link 61 with a lever 62 that engages a cam groove 63 of a cam wheel 64 on the shaft 12. The groove 63 is so shaped as to swing the lever 58 in one direction when the lever 14 is moved forwardly and the arm 21 moved rearwardly, and to move the lever 58 in the opposite direction when the movement of the lever 14 and arm 21 is reversed, the movement of the lever 58 occurring when the lever 14 and arm 21 change their direction of movement at the ends of their strokes. A lever 65 is also fulcrumed, as at 66, to the frame 29 and has one arm connected, as at 67, to the slide 30 for moving said slide up and down, and the other arm of the lever 65 has a pin or stud 68 projecting within a slot 69 in the lever 58, whereby the lever 65 is operated by the lever 58 with a limited lost motion. When the lever 58 is swung to raise the slide 35, it will move the pin 68 upwardly so as to move the roller 31 downwardly, and when the lever 58 is swung to move the slide 35 and cutter 36 downwardly, the lever 65 is swung to raise the roller 31, so that the roller 31 and cutter 36 alternate.

Gages or guides 70 are mounted on the table 1 at the opposite sides and are adjustable transversely to guide the blanks or objects in the proper longitudinal line of movement, so that the meeting edges of the blanks pass centrally under the tape applying means.

The operation of the machine is as follows:

Figs. 2 and 3 illustrate the mechanism in position to start the operation, the slide 7 being ready to move forwardly, with the wheel 31 raised. Then, as the shaft 12 completes one half of a revolution, the lever 14 is swung forwardly and the arm 21 rearwardly, the gripping member 22 sliding loosely back on the flange 23 so that the wheel 16 remains at a standstill, while the slide 7 will move the lowermost blank in the magazine forwardly the desired distance to bring the particular point of the blank on which the forward end of the tape is to be applied, under the center of the roller 31. The feeder slide 7 thus moves the blank forwardly to the proper position for the application of the forward end of the tape to the blank. Then, as the forward movement of the slide 7 is completed, and the lever 14 and arm 21 start to reverse, the cam 64 will swing the lever 62 so as to pull the link 61 downwardly, thereby raising the slide 35 and cutter 36, and as the cutter is raised, the slide 44 is moved forwardly, thereby feeding the tape forwardly with the finger 50 to bring the forward end of the tape under the roller 31. The forward end of the tape thus projects under said roller 31 beyond the end of the finger 50, and this movement takes place before the lever 58 has moved sufficiently to

move the lever 65, and during the completion of the movement of the lever 58, the lever 55 is swung to move the roller 31 downwardly, thereby pressing the forward end of the tape down on the blank. At this moment, the slide 7 starts its rearward movement, and the arm 21 moves forwardly, the member 22 gripping the flange 23 and turning the gear wheel 19 with the arm 21, whereby the feed wheel 16 is rotated, thereby feeding the blank which rests on said wheel by the pressure exerted by the roller 31. The amount of peripheral movement of the wheel 16 is controlled, as above explained, by the position of the wrist pin 25, and this will also control the length of the piece of tape applied to the blank. The wheel 16 thus rotates a predetermined amount during the forward movement of the arm 21 and the rearward movement of the slide 7 to place a desired length of tape on the blank, and as the parts resume the position illustrated in Fig. 2, the cam 64 swings the lever 62 to raise the link 61. This swings the lever 58 to move the slide 35 and cutter 36 downwardly, thereby cutting or shearing the tape 37, and withdrawing the finger 50 from over the cutting edge of the shear bar 34 before the cutter 36 comes into operation, because the slide 44 is moved rearwardly as the slide 35 is moved downwardly. As the slide 35 completes its movement, the lever 65 is moved by the lever 58, thereby raising the roller 31, so that the parts are restored to the position shown in Fig. 2, to repeat the operation.

Having thus described the invention, what is claimed as new is:—

1. A tape applying machine embodying tape applying means movable to present the end of a tape and press it against an object, means for feeding objects past said tape applying means and operable to move the objects to a predetermined position with respect to the tape applying means for the application of the tape and to then move the object a predetermined distance according to the length of tape to be applied to the object, and means for cutting the tape at a selected point of the object after the object has been moved as last stated.

2. A tape applying machine embodying means for feeding objects to a predetermined position, means movable for applying the end of the tape to the object in said position, means for feeding the object after the tape is applied for a predetermined distance according to the length of tape to be applied, and means for cutting the tape at a selected point of the object after the object has been moved the predetermined distance.

3. A tape applying machine embodying tape applying means, means for feeding objects to and past said tape applying means and operable for feeding an object to various

- predetermined positions with respect to the tape applying means for the application of the tape, and then operable for feeding the blank various predetermined distances according to the length of the strip of tape to be applied to the object, and means for cutting the tape at a selected point of the object after the object has moved the predetermined distance.
10. 4. A tape applying machine embodying feeding means for feeding objects and constructed and adjustable for feeding the objects to various predetermined positions, tape applying means for applying the end of a tape to the object in the predetermined position, feeding means operable for feeding the objects after the tape is applied and constructed and adjustable to move the objects various predetermined distances, and means for cutting the tape at a selected point of the object after the object has moved the predetermined distance.
15. 5. A tape applying machine embodying means for feeding a tape to be applied to an object, means for feeding objects to a predetermined position with respect to the tape and then moving the object a predetermined distance, means for pressing the tape against the object in the predetermined position, and
20. 30. means for cutting the tape at a selected point of the object when the object has moved a predetermined distance.
25. 6. A tape applying machine embodying tape applying means for applying a tape to an object in a predetermined position, feeding means constructed and operable for moving the object a predetermined distance after the tape is applied according to the length of the strip of tape to be applied, and means for cutting the tape at a selected point of the object after the object has moved the predetermined distance.
30. 7. A tape applying machine embodying a feeder wheel, means for feeding a tape to an object bearing against said wheel, means for pressing the tape against the object and the object against said wheel to apply the tape to the object and simultaneously feed the object, and means for cutting the tape when said wheel has rotated a predetermined amount in moving the object.
35. 8. A tape applying machine embodying means for feeding an object a predetermined distance, means for feeding a tape to the object, means for pressing the tape when fed against the object and bringing the feeding means into operation, and means operable for cutting the tape when the object has moved the predetermined distance.
40. 9. A tape applying machine embodying a feeder wheel rotatable a predetermined amount for feeding an object, means for pressing a tape against the object and the object against said wheel to feed the object a predetermined distance, means for feeding a tape between said pressing means and object, and means for cutting the tape when the object has moved the predetermined distance.
45. 10. A tape applying machine embodying means for feeding an object, means for pressing a tape against the object, a cutter for cutting the tape, tape feeding means movable back and forth and having a portion to move past the cutter for bringing the end of the tape between the object and said tape pressing means, and means for retracting the tape feeding means when the cutter is brought into operation and for retracting the cutter when the tape feeding means is advanced.
50. 11. A tape applying machine having means for applying tape over the meeting edges of a folded box or the like, means for pressing the tape on the object over said edges, and means extending under said pressing means for pressing the tape down between said edges.
55. 12. A tape applying machine embodying means for applying tape over the meeting edges of a folded box or other object, means for pressing the tape down on said edges, and a wire extending under said pressing means and arranged to press the tape between said edges.
60. 13. A tape applying machine embodying means for applying tape over the meeting edges of a folded box or other object, a roller for pressing the tape on the object over said edges, and a wire extending under said roller to press the tape between said edges, said roller having a groove partially receiving said wire.
65. 14. A tape applying machine embodying means for feeding an object, means for pressing a tape against the object, means for cutting the tape at a selected point of the object when moved by the feeding means, and means for advancing the tape past the cutting means to the pressing means to be applied to and pressed against the object.
70. In testimony whereof I have signed my name to this specification in the presence of two subscribing witnesses.
